(57) CLAIM

The ornamental design for a bidet, as shown.

DESCRIPTION

FIG. 1 is a perspective view of an embodiment of a bidet in a closed state with its cover on, in accordance with the design;

FIG. 2 is right-side view of the bidet of FIG. 1;
FIG. 3 is a left-side view of the bidet of FIG. 1;
FIG. 4 is a top view of the bidet of FIG. 1;
FIG. 5 is a bottom view of the bidet of FIG. 1;
FIG. 6 is a front view of the bidet of FIG. 1;
FIG. 7 is a rear view of the bidet of FIG. 1;
FIG. 8 is perspective view of the bidet of FIG. 1 in an open state with the cover removed;
FIG. 9 is a top view of the bidet of FIG. 8;
FIG. 10 is a bottom view of the bidet of FIG. 8;
FIG. 11 is a left-side view of the bidet of FIG. 8;
FIG. 12 is a right-side view of the bidet of FIG. 8;
FIG. 13 is a front view of the bidet of FIG. 8; and,
FIG. 14 is rear view of the bidet of FIG. 8.

The dashed broken line(s) define unclaimed subject matter and form no part of the claimed design.
